UNITED STATES PATENT OFFICE.

FRANCIS H. RICHARDS, OF HARTFORD, CONNECTICUT.

WEIGHING-MACHINE.

SPECIFICATION forming part of Letters Patent No. 578,163, dated March 2, 1897.

Application filed September 30, 1896. Serial No. 607,398. (No model.)

To all whom it may concern:

Be it known that I, FRANCIS H. RICHARDS, a citizen of the United States, residing at Hartford, in the county of Hartford and State of Connecticut, have invented certain new and useful Improvements in Weighing-Machines, of which the following is a specification.

This invention relates to weighing-machines, the object thereof being to provide an improved machine of this character which is readily adapted for automatically weighing and delivering various classes of materials with facility and precision, but more especially those of a dusty nature.

15 In the drawings accompanying and forming part of this specification, Figure 1 is an end elevation of a weighing-machine comprising my present improvements and illustrates the positions occupied by the respective parts at the commencement of operation, a portion of the framing being removed to show more clearly certain peculiar features of the invention. Fig. 2 is a rear elevation of the machine, a portion of the door by which access

20 is had to the interior of the hollow base and column being removed to illustrate the disposition of the incased mechanism. Fig. 3 is an end elevation as seen from the opposite end of the machine from Fig. 1 and illustrates

25 more particularly the closer-latching means and tripping device for the latch. Fig. 4 is a view somewhat similar to Fig. 2, the framing being in section, taken in line *b b*, Fig. 1, and showing the operative parts in a different po-

30 sition. Figs. 5 and 6 are detail views, in end and rear elevations, respectively, of the upper and lower parts of the machine. Fig. 7 is a view somewhat similar to Fig. 1, the lower part of the bucket and the adjacent portion 35 of the base being broken away to show the closer mechanism, said closer being in its wide-open position. Figs. 8 and 9 are detail views, in rear elevation, of the bucket and beam mechanisms and adjacent parts, showing a

40 method of obtaining a test. Fig. 10 is a sectional plan view showing the peculiar disposition of the beam mechanism, the section being taken in line *a a*, Fig. 1. Fig. 11 is a detail view, in central vertical section, of a dust- 45 guard; and Fig. 12 is a transverse section in line *c c*, Fig. 11.

Similar characters designate like parts in all the figures of the drawings.

The framework for supporting the operative parts of the machine comprises the hollow or chambered base 2 and the hollow column or upright 3 rising therefrom, the chambers of said base and column communicating with each other.

The more sensitive parts of the machine 55 will be incased or housed within the base 2 and column 3, respectively, so that they may be protected from the deleterious action of dust, dirt, &c., and the machine consequently rendered certain in its operation.

60 The weighing mechanism comprises two counterweighted scale-beams, the weights of which are provided with bucket-supporting arms extending away from each other, and a bucket carried by said arms, whereby such 65 scale-beams may be compactly disposed within the base, occupying, as will be apparent, a minimum amount of space, which is an important essential, especially in large-sized machines.

70 The base 2 is substantially U-shaped in horizontal section, and it has the interior longitudinal chambers 4 and 5 and the transverse chamber 6, in the first-mentioned two of which the weights *W* and *W'* are longitudinally disposed, said weights being preferably cylindrical.

75 The bucket-supporting arms of the beam *B* are designated by 7 and 8, the corresponding arms of the beam *B'* being designated by 7' and 8', respectively. A second pair of arms is shown at 9 and 9', oppositely extending into the transverse chamber 6 from the weights *W* and *W'*, respectively, said arms being furnished with knife-edges, which rest on 80 notched bearings seated in the blocks extending upward from the bottom plate of the base 3, the arms 7 and 7' being similarly equipped, whereby the two beams are properly supported.

90 The bucket is designated by *G* and about midway of its depth tapers toward the usual discharge-outlet, which in the present instance is circular in shape and permits the ready discharge of the load. The bucket is 95 furnished with depending brackets 10 and 10' suitably attached thereto and having enlarge-

ments in which are formed sockets for the reception of the vertical posts 12 and 12', which pass through openings formed in the upper part of the base 3 and are joined to the 5 curved transverse bars 13, which latter carry, adjacent to the opposite ends thereof, notched bearings resting on knife-edges or equivalent supports carried by the beam-arms 7 and 8 and 7' and 8', respectively.

10 As a means for preventing the entrance of dust, &c., through the openings through which the rods 12 and 12' pass I employ a dust-guard, which in the present instance is in the form of an extensible bellows-like envelop of pliable material. (See Fig. 11.)

15 A ring is shown at 14, disposed about the post-opening, a similar ring being shown at 15, attached to the post 12, such rings being joined by the bellows-like envelop 16, to which 20 I have just referred, whereby the hereinbefore-mentioned object may be obtained.

25 I have described in detail but one of the dust-guards, or that illustrated in Figs. 11 and 12, its mate being the same in construction.

For the purpose of increasing the leverage exerted by the beams B and B' the weights W and W' thereof are furnished with the laterally-extending counterweighted arms 17 30 and 17', said arms being operatively connected by means of the link 18, whereby a movement in unison of the two beams is secured.

For controlling the discharge-outlet of the 35 bucket I prefer to employ the closer mechanism shown, which is designated in a general way by L and consists of a flat circular plate or closer proper, 19, suitably supported for rotative movement. The closer 19 is furnished with a projecting spindle 20, which is seated in a bearing formed in the counterweighted yoke 21, the members of the latter being pivotally supported by the bucket G, the office of the counterweights being to return the closer to its normal or shut position on the discharge of a bucket-load.

For imparting the requisite rotation to the closer as it opens, a pawl and ratchet will be 50 preferably employed, such ratchet being designated by 22 and being suitably attached to the bucket, and its teeth will be engaged by a suitable pawl, such as that illustrated at 23. The pawl 23 is pivotally mounted on the bracket 24 and will be also counterweighted, 55 whereby its point will be maintained in constant engagement with the teeth of the ratchet 22, the latter being circular.

For maintaining the closer 19 in its normal 60 position or tight against the lower edge of the bucket G the following instrumentalities may be employed: A relatively short rock-shaft is shown at 25, mounted on the bucket and having a rock-arm 26, to which is pivoted the relatively long rod 27, said rod being 65 similarly connected to the lug 28, projecting centrally from the upper face of the closer 19, and also passing through the bucket, so

that the closer when latched may be maintained in the shut position without sagging, thereby obviating a frequently-existing difficulty. The shaft 25 also has the arm 29, which is in position to be engaged by a suitable closer-latch when the closer is shut. 70

The closer-latch is designated by 30 and is counterweighted, it being furnished with an 75 angular shoulder 31, against the inner face of which the projecting arm 29 on the rock-shaft 25 is adapted to bear when the closer is shut. (See Fig. 3.) When the shoulder 31 is disengaged from the free end of the arm 80 29, the closer 19 will be released and may be forced open by the weight of the contents or load within the bucket, during which action it will be rotated by the counterweighted pawl 23, which is in engagement with the circular 85 ratchet 22 on the bottom of the closer, so that on such rotation particles of material will be prevented from adhering to the closer.

From the foregoing description of the closer mechanism it will be evident that my present invention includes, in connection with 90 weighing mechanism embodying a bucket and a closer for said bucket, means for imparting to said closer a step-by-step or intermittent movement on one of its strokes—in 95 the present instance as it opens—whereby the mass of material sustained by said closer will be positively dislodged or shaken therefrom.

In the modification of the invention herein 100 illustrated I have shown mechanism for effecting a rotary step-by-step movement of the closer, but it is distinctly to be understood that the invention is not to be so limited.

For supplying the bucket G with a stream 105 of material the supply hopper or spout H, which is suitably joined to the column or standard 3, may be employed.

The lower or stream-directing wall of the chute or hopper H is inclined downward toward the bucket, it also having a vertical lip 32, by which the course of the flowing stream is changed, so that such stream is not directed 110 against the forward part of the stream-controlling valve 33, the power necessary to effect 115 the closure of said valve being thereby considerably reduced.

I have shown located within the hopper or chute H and suitably attached to a wall thereof a flexible apron or detent device 34, which has a series of weights or ribs 35 secured thereto at suitable intervals, which serve to hold said apron against the stream, the ribs taking a firm hold of the mass, whereby its speed will be checked, said apron also preventing scattering of the material when it flows in a very fine stream. 120

It is necessary in weighing different classes of materials to supply the same in streams of different volumes to the bucket, and for adapting my present machine to this work I have 125 illustrated herein means for quickly changing the size of the supply-stream. The stream-regulating means shown consists of a pivot-

ally-supported plate 37, constituting the front wall of the discharge-outlet of the hopper H, said plate 37 being furnished with a projecting crank-arm 38, having a suitable pin 5 adapted to be seated in any one of a series of recesses formed in an end wall of the chute, whereby the plate 37 may be held in an adjusted position, as will be understood.

The valve 33, which is controlled by the weighing mechanism, is oscillatory beneath the discharge-outlet of the chute H, it being pivotally supported between the forward projecting arms 39 and 40 of the column 3.

The mechanism for effecting the closure of the valve 33, which is shown in its wide-open position in Figs. 1 and 2, will now be described. A relatively short rock-shaft is illustrated at 41 passing through and supported by one of the walls of the column 3, it being provided at 20 its outer end with a crank-arm 42, which is connected by the interposed link 43 to the valve 33, said rock-shaft 41 having on its inner end the crank-arm 44, connected by a universal joint to the relatively long thrust-rod 25 45. A valve-closing cam is illustrated at 46, it being operative with the valve and pivotally mounted within the hollow column or upright 3, its angular arm 46' being operatively connected, by means of the link 47, to the thrust-rod 45. The cam is positioned to be engaged by a suitable device for oscillating the same, whereby such motion will be transmitted to the valve 33 through the described connections for effecting its closure.

35 There are located within the hollow column or upright 3 two operatively-connected levers, (designated by 48 and 49, respectively,) said levers being connected by the link 50. The lever 48 is furnished with an antifriction-roll 48', which is adapted successively to engage the connected working faces 51 and 51' of the cam 46, the last-mentioned face being of such shape as to permit the exertion of a relatively great amount of leverage on said cam to effect 45 the final and rapid closure of the valve for cutting off the last part of the supply-stream. The lever 49 is furnished with an adjustable counterweight 52.

The operation of the valve-closing mechanism just described will be apparent from an inspection of Figs. 1, 2, and 4. The lever 49 being at the limit of its upstroke, as indicated in Fig. 2, and dropping, (such action, however, being limited by suitable means,) the roll-arm 55 of the lever 48 will be thrust upward, and, the roll 48' traveling along the cam-face 51, the cam 46 will be swung to the left in correspondence with the movement of the lever 49, and as said cam swings an upward thrust will be 60 imparted to the rod 45, and the link 43, by reason of its connections with the rod 45, will be moved to the left, (see Fig. 1,) whereby the valve 33 will be closed. When the roll 48' has reached the intersection of the two cam-faces 65 51 and 51', as indicated in Fig. 4, the valve 33 will be momentarily held to permit the flow of a drip-stream into the bucket G for the pur-

pose of completing the partial load therein. When the valve is released, the roll 48 will be caused to travel rapidly along the cam-face 70 51' by the sudden dropping of the counterweighted lever 49, so that the final closing movement of the valve will be a rapid one, and during this last-mentioned movement a supplemental or drip valve will be brought 75 into play for cutting off the last part of the drip-stream.

The supplemental or drip valve is designated by 53, it consisting of a blade pivotally supported near the discharge end of the main 80 valve 33, an extended pivot of said supplemental valve being furnished with a crank-arm 54, having a roll 55, which is caused to impinge against the working face of the cam 56, constituting an extension of a wall of the 85 chute H, so that when the valve 33 is given its final closing movement the roll 55 will be caused to travel along the face of the cam 56, and the supplemental or drip valve 53 will be thrust upward, as indicated in Fig. 7, for 90 cutting off the drip-stream, as will be obvious.

On the opening movement of the valve 33 the supplemental or drip valve 53 will simply drop to its normal position as the roll 55 leaves the effective face of the cam 56.

95

For opening the valve 33 to permit the flow of the supply-stream into the bucket the following mechanism will be employed: A valve-actuating device in the form of a counterweighted lever is shown at 57, shiftably supported by the beam B, it being pivoted at one end to an ear or lug 58 on the weight W, said lever normally forming a part of the counterpoised weight and being sustained during such period by the pin 59, which extends from the weight 17". (See Fig. 10.) The thrust-rod 45 terminates in a hook or stirrup 60, against the horizontal portion of which the projection or roll 61, mounted on the lever 57, is adapted to bear during the 110 major period of operation, as indicated in Fig. 2, said lever exerting a force in excess of the counterweighted valve-closing lever 49.

The operation of the valve-opening mechanism is as follows: Fig. 2 represents the 115 counterweighted lever 57 in its normal position, it resting against the pin 59 on the weight 17". The valve being wide open and the closer shut, a stream of material will flow into the bucket, and when a certain proportion of the load has been received by the bucket it and the poising sides of the two beams B and B' will descend, the counterpoised sides of said beams ascending and the lever 57 rising therewith, and its roll 61, moving away from 120 the horizontal portion of the hook 60, will permit the upward thrusting of the rod 45 by means of the coacting levers 48 and 49 and the cam 46, which is connected to said rod, whereby the valve 33 will be closed, 125 the movement of the cam 46 being in unison with the beam mechanism and hence the lever 57. When the valve has reached its closed position, the closer will be opened, and con-

currently therewith the valve will be locked against return movement during the load-discharge period. As the load empties, the bucket will rise, the counterpoised sides of the two beams of course descending. While the valve is locked against return movement, the thrust-rod 45, through its connections with said valve, will be likewise held, and its hook 60 being in engagement with the roll 61 of the counterweighted lever 57 the return movement of said lever with the beam will be blocked, as will be understood. When the valve is released, the rod 45 and lever 57 will be freed also, and as the latter returns to its normal position it will draw the thrust-rod 45 downward, and in so doing the valve 33, by reason of its operative connections with said thrust-rod, will be opened.

I have illustrated herein reciprocally effective stops operative, respectively, with the valve and with the closer, they being in the form of skeleton segments 62 and 63, the first-mentioned rigidly depending from the valve, the coöperating member being suitably affixed to the rock-shaft 25. While the valve 33 is open, the segment 63 will be contiguous to the curved face of the segment 62, so that should the latch 30 be tripped the oscillation of the segment 63 will be prevented by the co- operating member 62, and said relation will continue until the valve 33 has reached the end of its cut-off stroke, the opening of the closer 19 being also prevented. When the valve has reached the end of its cut-off stroke, the segment will have crossed the plane of the curved face 63, so that the latter may oscillate, and when the latch 30 is tripped the curved face of said segment 63, when it rocks, will be approximately in contact with the point 62' of the segment 62, so that retractive movement of the latter will be arrested, the valve 33 of course being locked in its closed position and being so maintained until the closer 19 is shut, when the valve 33 and connected parts will be unlocked.

The valve 33 will be intercepted at a predetermined point in its closure to permit the flow of a reduced or drip stream into the bucket, and for this purpose the following instrumentalities will be employed: The pivot-pin 45' is shown having joined thereto the vertical rod 64, the lower end of which is pivoted to an angular arm 65' of the lever 65, said lever being supported for oscillation within the chamber of the column 3 and having at its lower end a shoulder 66.

It will be understood that the lever 65 operates in unison with the thrust-rod 45, and that when its movement is arrested said thrust-rod, and hence the valve 33, will be checked.

A counterweighted by-pass stop is illustrated at 67, it being pivoted to a projection on the weight W, the upright arm of said by-pass having a shoulder 67', which is adapted to engage the coöperating shoulder 66 on the lower end of the lever 65 at the commencement of the poising period. As the thrust-

rod 45 moves upward, the free arm of the lever will be swung to the left, and the by-pass 67 rising with the weight of the beam B the shoulder of said by-pass will engage the shoulder 66 on the lever 65, so that the thrust-rod and connected parts may be held against further progress. At about the time the parts are thus held the antifriction-roll 48' will be at about the intersection of the cam-faces 51 and 51', as indicated in Fig. 4. When the load is completed, the shoulder 67' will be thrust above the shoulder 66, so that the lever 65, the thrust-rod 45, and the valve 33 will be released, as also the lever 49, and the latter dropping the roll 48' of the lever 48 will be caused to ride along the cam-face 51', whereby said cam will be given a quick movement for effecting an instantaneous and final closure of the two valves 33 and 53 for cutting off the supply.

For tripping the latch 30 the following mechanism may be employed: A rock-shaft is illustrated at 68 journaled in the opposite walls of the column or upright 3 and extending therefrom, said shaft having the lug 69, which is disposed in the path of movement of the projection 70 on the thrust-rod 45. The shaft 68 carries at its outer end the latch-tripper or arm 71, which is adapted to impinge against the arm 72, integrally formed with the closer-latch 30. At the commencement of the poising period the projection 70 will be adjacent to the lug 69 on the shaft 68, it being understood that the valve and connected parts are temporarily held. When said valve is released, the projection 70 will be caused to abut against the lug 69 on the upward movement of the thrust-rod 45, so that on the continuation of said movement the shaft 68 is rocked and the arm 71 will be caused to impinge or bear against the arm 72 of the latch 30, whereby the shouldered member of said latch will be depressed and the shoulder 31 disengaged from the free end of the arm 29, so that the closer 19 will be released, at which time it may be forced open by the weight of the contents within the bucket.

In connection with the machine means are provided for weighing out fractional parts of a load. A load-beam is shown at 75, it being in the present instance formed integral with the weight W of the scale-beam B, said load-beam being furnished with a sliding weight 76, which is longitudinally reciprocatory within the transverse chamber 5 of the base and toward and from a zero or arbitrary point on said load-beam, the latter being suitably graduated—though said graduations are not shown herein—to either add to or subtract from the total weight of the bucket mechanism.

A set-screw is shown at 77 passing through the weight 76, it being adapted to bind against the load-beam 75 and hold said weight in an adjusted position.

It is desirable at infrequent intervals to make tests to ascertain if the machine is

weighing properly, and I have provided means for this purpose, which will now be described. One of the walls of the column 3 is shown supporting the rock-shaft 80, the latter being furnished at its outer end with a crank-arm 81, secured thereto by a pin, said rock-shaft having at its inner end the screw 82, which is embraced by the reciprocatory nut or collar 83, connected by a link 84 to a thrust-rod 45, so that as said shaft 80 is rocked the nut or collar 83 will be reciprocated back and forth to draw the thrust-rod 45 away from and return it to its normal position. The crank-arm 81 has the thumb-piece 85, to which is connected the pin 86, which is adapted to enter one of a series of recesses, as 87, formed in the outer face of the column 3. (See Fig. 3.)

During the major period of operation of the machine the pin 86 will be seated in the uppermost one of the series of recesses 87, whereby the rod 45 will be maintained in its vertical or normal position.

To make a test, the pin 86 will be withdrawn from the uppermost recess, and the crank-arm 81 will be revolved and said pin thrust into the intermediate recess of the series, as indicated in Fig. 8, so that the thrust-rod 45 will be oscillated to the right through the medium of the described connections, and the projection 70 will be carried beyond its plane of effective action, and as said rod continues its upward movement during the weighing of a load said projection does not abut against the lug 69 on the rock-shaft 68. The latch 30 therefore not being tripped and a true load being in the bucket, the loaded bucket and beam mechanism, after a few slight oscillations, will assume an equipoised position.

During the operation just described the hook 60 will be in engagement with the projection 61 on the counterweighted lever 57, which forms a part of the beam mechanism, so that the closing movement of the valve 45 will be checked or limited by the beam mechanism. When the valve has reached the end of its cut-off movement, the thumb-piece 85 will be again grasped and the pin 86 withdrawn from the intermediate recess of the series and the crank-arm 81 further revolved until the pin 86 is opposite the lowermost recess of the series, into which it is then thrust, the hook 60 having been disengaged from the projection 61, the rod 45 thereby being thrown out of operative connection with the beam mechanism, so that the bucket, having received a true load, will assume an equipoised position with the beam mechanism. If otherwise, the difficulty may be seen and remedied.

I have provided means for preventing the rotative movement of the collar or nut 83 when a test is being made, such means consisting of a fixed pin 92, extending inward from the column 3 and passing through an eye formed in the arm or extension 93 of the nut or collar 83.

The connected base and column 3 have formed therein a relatively wide opening closed by a door 90, by which access is had to the interior of the said base and column, said door being suitably hinged near its lower end to the base 2 and being also held tightly closed by a suitable catch, as 91, which engages some part of the framing. When the door 90 is open, the entire weighing mechanism and operative parts which are incased will be disclosed to view for any purpose.

The operation of the hereinbefore-described weighing-machine is as follows: Fig. 1 represents the positions occupied by the various parts at the commencement of operation, the closer 19 being held in its shut position by the latch 30, which is in engagement with the arm 29 on the rock-shaft 25, the latter being connected to said closer. The valve 33 being wide open, a stream of material of large volume will flow into the bucket G from the chute or hopper, and when a certain proportion of the predetermined load or charge has been received by the bucket it and the poising sides of the two beams B and B' will descend, the counterpoised sides of said beams ascending, and the roll 61, leaving the hook 60 of the thrust-rod 45, will permit the latter to rise, so that the counterweighted lever 49 may drop, and in so doing said lever will impart an opposite stroke to the lever 48, the roll 48' of which is caused to ride along the face 51 of the cam 46 and oscillate the latter to the left, whereby the valve 33 will be partially closed by reason of its operative connections with said cam. At about the time the roll 48' reaches the intersection of the cam-faces 51 and 51' the shoulder 67' of the by-pass 67 will engage the coöperating shoulder 66 on the lever 65 and will hold said lever, and consequently the valve 33, which is connected thereto, against further movement. On the completion of the bucket-load the bucket and poising sides of the beams will descend farther, the by-pass 67 being elevated and its shoulder 67' raised clear of the shoulder 66 on the lever 65, thereby releasing the valve, and the valve-operating lever 49 dropping farther the roll 48' will be caused to travel along the cam-face 51' for imparting an accelerated and final closing movement to said valve 33 for cutting off the last part of the supply-stream. During the final movement of the thrust-rod 45 the projection 70 thereon will be caused to abut against the lug 69 on the rock-shaft 68, thereby rocking said shaft and concurrently oscillating the arm 71, whereby said arm will be caused to impinge against the arm 72 of the latch 30, so that the shouldered member of said latch will be depressed and the shoulder 31 disengaged from the arm 29 of the rock-shaft 25, this action releasing the closer 19.

While I have shown a rotary closer as the preferred form to be used, it is obvious that other kinds of intermittently-movable closers are within the purview of my invention.

No claim is herein made to the combination, with weighing mechanism including a bucket, of a closer and means for imparting to the closer a step-by-step movement, such subject-matter being set forth and claimed in my application filed April 27, 1896, Serial No. 589,219.

Having described my invention, I claim—

1. The combination with weighing mechanism embodying two counterweighted scale-beams the weights of which have bucket-supporting arms, said arms extending away from each other, and a bucket carried by said arms; of a supply-hopper; a valve for said hopper, controlled by the weighing mechanism; a load-beam formed integral with and extending from one of the beam-weights; a sliding weight on said beam; and means for maintaining said sliding weight in an adjusted position.
2. The combination with a hollow base having two longitudinal chambers and a communicating transverse chamber, of weighing mechanism embodying two counterweighted scale-beams supported for movement within said longitudinal chambers; and a bucket carried by said scale-beams; a load-beam connected to one of said beam-weights; a weight longitudinally movable in the transverse chamber and sliding on said load-beam; and means for maintaining said sliding weight in an adjusted position.
3. The combination with a hollow base having two longitudinal chambers, of weighing mechanism embodying two counterweighted scale-beams the weights of which are located in said longitudinal chambers, said weights also having arms extending away from each other; a bucket; and posts connected to said bucket and passing through openings in the base, said posts having transverse bars provided with notched bearings resting on knife-edges on the beam-arms.
4. The combination with a hollow base having two longitudinal chambers, of weighing mechanism embodying two counterweighted scale-beams the weights of which are located in said longitudinal chambers, and a bucket; posts connected to the bucket and passing through openings in the base, each of said posts being joined to a transverse bar provided with notched bearings resting on knife-edges on the scale-beams; and dust-guards disposed about said openings.
5. The combination with a hollow base having two longitudinal chambers and a communicating transverse chamber, of weighing mechanism comprehending a pair of counterweighted scale-beams located in the longitudinal chambers; a bucket; posts connected to said bucket and passing through openings in the base, each of said posts being joined to a transverse bar provided with notched bearings resting on knife-edges on the scale-beams; a weighted load-beam extending from one of the beam-weights, the weight of said load-beam being longitudinally adjustable in said transverse chamber; rings disposed about

said openings; complementary rings on said posts, joined to the other rings by extensible dust-guards disposed about said posts; and a hopper having a valve controlled by the weighing mechanism.

6. The combination with a base having interior longitudinal and transverse chambers, of weighted beams supported in the longitudinal chambers in parallelism with each other and extending into the transverse chamber; arms outwardly projecting from each of said beams, the arms of one beam projecting in an opposite direction from those of the other; connected laterally-extending counterweighted arms projecting from said beams; and a load-receiver supported by the outwardly-projecting arms, for the purpose specified.

7. The combination with a U-shaped base having interior longitudinal and transverse chambers, of weighted beams supported in the longitudinal chambers in parallelism with each other and extending into the transverse chamber; a series of separated arms outwardly projecting from one side of each of said beams, the arms of one beam projecting in an opposite direction from those of the other; laterally-extending counterweighted arms connected together and projecting from the inner sides of said beams; and a load-receiver supported by the series of outwardly-projecting arms, for the purpose specified.

8. The combination with weighing mechanism embodying a bucket, of a supply-hopper; a valve for said hopper; a rod operative with said valve; a rock-shaft having a screw; and a collar embracing said screw and operatively connected to said rod.

9. The combination with weighing mechanism embodying a bucket, of a supply-hopper; a valve for said hopper; a rod operative with said valve; a rock-shaft having a screw; a collar embracing said screw and operatively connected to said rod; and a crank-arm on said shaft.

10. The combination with weighing mechanism embodying a bucket, of a supply-hopper; a valve for said hopper; a rod operative with said valve; a rock-shaft having a screw; a collar embracing said screw; and a link pivotally connected, respectively, to said collar and rod.

11. The combination with a bucket and beam mechanism for supporting the same, of a supply-hopper; a valve for said hopper; a rod co-operative with the valve and beam mechanism; a rock-shaft having a screw; and a collar embracing said screw and operatively connected to said rod.

12. The combination, with a bucket having a closer, of means including a latch for holding said closer against movement; a shaft mounted in the framework, said shaft carrying a lug; a latch-tripper connected to the outer end of said shaft; a hopper; a valve for said hopper; a rod operatively connecting said valve and provided with a projection for engaging said lug; and means for shifting said

- rod, whereby on the upstroke thereof it will engage the lug, rock the shaft, and trip the latch.
13. The combination with weighing mechanism embodying a bucket, of a supply-hopper; a valve for said hopper; a rod operative with said valve; a rock-shaft having a screw; a collar embracing said screw and operatively connected to said rod; and a guide for said rod.
14. The combination with weighing mechanism embodying a bucket, of a supply-hopper; a valve for said hopper; a rod operative with said valve; a rock-shaft having a screw; a collar embracing said screw and having an arm provided with an eye; and a pin passing through said eye.
15. The combination with beam mechanism and a bucket supported thereby, of a lever shiftably supported by the beam mechanism; a hopper; a valve; and a rod operatively connected to said valve and having a hook for normally engaging a projection on said shiftable lever.
- 25 16. The combination with beam mechanism and a bucket supported thereby, of a lever shiftably supported by the beam mechanism; a hopper and its valve; a rod operatively connected to said valve and having a hook for normally engaging a projection on said lever; and shifting means for said rod.
17. The combination with a pair of counterweighted scale-beams the weights of which are furnished with counterweighted arms, of a lever shiftably connected to a lug on one of the beam-weights and resting on a stud on the weight of one of said arms; a bucket; a hopper; a valve for said hopper; and a rod operatively connected to said valve and having a hook adapted to engage a projection on said shiftable lever.
18. The combination with a hopper, of a valve therefor; a cam operative with said valve; and two operatively-connected levers, one of which is adapted to actuate said cam.
19. The combination with a hopper, of a valve therefor; a cam operative with said valve; and two operatively-connected levers, one of which is adapted to actuate said cam, the other lever being counterweighted.
20. The combination with a hopper, of a valve therefor; a cam operative with said valve; a lever adapted to actuate said cam; a counterweighted lever; and a link pivoted, respectively, to said levers.
21. The combination with beam mechanism, of a bucket supported thereby; a hopper; a valve; a rod coöperative with the beam mechanism and with said valve; a cam operative with said valve; and a pair of operatively-connected levers, one of which is adapted to actuate said cam.
22. The combination with weighing mechanism embodying a bucket, of a supply-hopper; a valve therefor; a lever operatively connected to said valve; and a stop mounted on the beam mechanism and adapted to engage said lever at a predetermined point to thereby hold said valve.
23. The combination with beam mechanism and a bucket, of a hopper; a valve; a lever; a rock-shaft operatively connected, respectively, to said valve and lever; and a stop adapted to successively engage and release said lever at predetermined points.
24. The combination with a bucket having a closer, and means embodying a latch, for holding the same against movement; a rock-shaft having a lug; a reciprocatory rod having a projection adapted to engage said lug; a latch-tripper on said shaft; a second rock-shaft operatively connected to the closer and having a stop; a hopper and its valve provided with a stop coacting with said first-mentioned stop.
